UNITED STATES PATENT OFFICE.

MICHAEL F. CUBIAC, OF DETROIT, MICHIGAN, ASSIGNEE OF FORTY-EIGHT ONE-HUNDREDTHS TO JOHN A. SWANSON, OF DETROIT, MICHIGAN.

CLOTHES-LINE HOLDER AND FASTENER.

1,265,620.

Specification of Letters Patent.

Patented May 7, 1918.

Application filed May 19, 1916. Serial No. 98,619.

To all whom it may concern:

Be it known that I, MICHAEL F. CUBIAC, a citizen of the United States, residing at Detroit, in the county of Wayne and State 5 of Michigan, have invented certain new and useful Improvements in Clothes-Line Holders and Fasteners; and I do hereby declare the following to be a full, clear, and exact description of the invention, such as will enable others skilled in the art to which it 10 appertains to make and use the same.

This invention relates to new and useful improvements in a clothes line holder and fastener and one of its objects is the provision of a device of this character, which shall be simple, durable and efficient, and which may be manufactured and sold at a comparatively low cost.

Another object of this invention is to provide an attaching base, having an arm pivoted thereto, which has a pulley journaled thereon for receiving one end of a clothes line and having means on its other end for gripping or binding the end of the clothes line into an engagement with the attaching base, to prevent the line from becoming detached from its support.

A further object of this invention is to provide an extension upon the lower end of 30 the attaching base plate having a pair of relatively spaced guide lugs for receiving the end of the clothes line after said line has been passed over the pulley and which is clamped by the lower end of the arm, under 35 the influence of the weight of the line upon the pulley.

A still further object of this invention is to provide a bracket, having a vertically extending pulley thereon, whereby a number 40 of said brackets may be arranged upon posts for supporting the clothes line between its ends.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which:

Figure 1 is a fragmentary perspective 55 view of a clothes line holder and fastener

applied to supporting posts, having a clothes line attached thereto,

Fig. 2 is a front elevation of a clothes line fastener, constructed in accordance with my invention,

Fig. 3 is a vertical sectional view of the same,

Fig. 4 is a side elevation of the clothes line holder, and

Fig. 5 is a front elevation of the same.

Referring in detail to the drawing, the numeral 1 indicates a plurality of supporting posts having my invention applied thereto.

The end supporting post has secured thereto an elongated base plate 2, which is 70 provided with countersunk openings 3 for receiving screws for securing the same to the post. A pivot lug 4 is formed upon the attaching base plate 2 intermediate its ends

and has secured thereto a bolt 5 for pivotally supporting a clamping lever 6. A suitable nut 7 is carried by the bolt 5 for retaining the arm 6 thereon. The arm 6 is provided with its upper end bent upwardly and outwardly as illustrated at 8 and having an 80 enlarged portion 9 formed upon its end.

A transversely extending bolt 10 is carried by the enlarged portion 9 of the lever 6 and has journaled thereon a grooved pulley 11, which is supported in vertical alinement 85 with the arm 6.

The lower end of the lever 6 is provided with a pair of relatively spaced guide lugs 12 upon the under side thereof for receiving the end of a clothes line 13 after it has been passed over the pulley 11. 90 The under side of the lever 6 adjacent the pivot point thereof is provided with a vertically extending groove for receiving the clothes line as it passes downwardly from the pulley 11 to the guide lugs 12.

Formed on the lower end of the attaching plate 2 and extending at right angles thereto is a clamping arm 14 having formed thereon adjacent its lower edge a pair of relatively spaced guide lugs 15 for receiving 100 the free end of the clothes line 13 after passing between the guide lugs 12 of the lever 6. A plurality of transversely extending ribs 16 are formed on the arm 14 above the guide lugs 15 for biting into the clothes line 13 when pressed thereon by the lower end of the lever 6.

The weight of the clothes line upon the pulley 11 will cause the lower end of the lever 6 to move in the direction of the arm 14 binding or gripping the end 110

of the clothes line 13 against the ribs 16, thus preventing the clothes line from becoming detached from the pulley 11.

A suitable bracket 17 is provided with 5 countersunk openings 18 for receiving screws for attaching said bracket to the intermediate posts. An upwardly and outwardly directed extension 19 is formed upon the upper end of the bracket 17 and is enlarged as 10 illustrated at 20 to form a supporting base, which has formed thereon a guard 21 extending in the direction of the vertical plane of the bracket 17. A suitable bolt 22 is secured to the base 20 and has journaled 15 thereon a grooved pulley 23. The clothes line 13 has one of its ends secured to the attaching plate 2 and is then passed around a number of the pulleys 23 carried by the bracket 17 upon the intermediate posts arranged within a yard and the other end of 20 the clothes line is then attached to another attaching plate 2, upon the other end post.

The weight of clothing suspended upon 25 the clothes line 13 will cause a pulling action upon the pulley 11 of the attaching plate 2 and will cause the lower ends of the levers 6 to clamp tighter upon the free ends of the clothes line 13 as the weight upon said clothes line is increased, thus obviating the 30 danger of the clothes line 13 slipping or becoming accidentally disengaged from the end post under a heavy load. By pulling upon the free end of the clothes line 13 away from the attaching plate 2, the lever 6 is 35 caused to swing upon its pivot, whereby the clothes line may be withdrawn from between the lower end of the lever 6 and the plate 14, when desiring to remove the clothes line from the posts 1.

40 While I have shown and described the preferred embodiment of my invention, it will be understood that minor changes in construction, combination and arrangement of parts may be made without departing

from the spirit and scope of the invention 45 as claimed.

Having thus described my invention, what I claim is:—

A device of the character set forth comprising a vertically disposed elongated base 50 plate, a pivot lug extending outwardly from the outer face of the base plate at a point between the ends thereof, a clamping arm located at the lower end of the base plate and extending laterally from one side edge 55 thereof and having its outer face serrated, a bolt carried by the pivot lug and extending laterally therefrom beyond said side edge of the base plate and located outwardly beyond said clamping arm, an angle clamping lever 60 vertically disposed and pivoted intermediate its ends to said bolt, one arm of said lever extending downwardly and inwardly from said bolt in the direction of said clamping arms and having a vertical clamping face 65 coacting with the serrated face of said clamping arm, a pair of relatively spaced lugs extending outwardly from the outer face of said clamping arm at a point below the lower end of said lower arm, a pair of 70 relatively spaced lugs extending inwardly from said lower arm at a point above said clamping arm, the upper arm of said clamping lever extending laterally and outwardly and thence upwardly and outwardly with 75 respect to said lever arm, a bolt carried by the upper end of said upper arm and extending laterally therefrom in the direction of and arranged parallel to said base plate, and a grooved roller journaled upon said 80 last named bolt.

In testimony whereof I affix my signature in presence of two witnesses.

MICHAEL F. CUBIAC.
